(57) **ABSTRACT**

A coil apparatus includes a coil unit including a coil, a base core that is a first core component, and a core module that is a second core component. The first core component includes a center leg that is a leg around which the coil is wound. The second core component includes a plurality of core segments arranged in a row with gaps between them. The second core component is connected to the leg to form a magnetic path together with the first core component.

POWER CONVERTER AND COIL APPARATUS

FIELD

The present invention relates to a coil apparatus including a coil, and a power converter.

BACKGROUND

To provide a smaller and higher-power-density power converter, it is effective to use planar coil apparatuses that are easily cooled by heat dissipation to a housing or the like, as coil apparatuses such as a transformer and a reactor that occupy large areas in a power converter. A planar coil apparatus is also referred to as a low-profile coil apparatus. In a planar coil apparatus, magnetic paths are formed by a combination of an E-shaped core and an I-shaped core, a combination of an E-shaped core and an E-shaped core, or the like.

A coil apparatus needs to be precisely adjusted in gap length that is the length of a gap between cores, to obtain a desired inductance value. The gap length is sometimes adjusted by fixing cores to each other with a gap sheet sandwiched between polished surfaces of the cores. It is known that, in this case, variations in the dimensions of the gap sheet or variations in the precision of polishing of the cores result in variations in inductance value. The longer gap length the coil apparatus has, the larger the leakage flux. When the leakage flux becomes larger, the magnetic flux causes eddy currents to flow in a coil constituting the coil apparatus, increasing loss in the coil.

Patent Literature 1 discloses a coil apparatus with a combination of an I-shaped core and an E-shaped core, in which gaps are formed between the I-shaped core and the E-shaped core using a bobbin that holds a coil. According to the technique of Patent Literature 1, the gap length can be set with high precision without using a gap sheet. In the coil apparatus of Patent Literature 1, the gaps are distributed among the legs of the E-shaped core to suppress leakage of flux per gap.

CITATION LIST

Patent Literature

Patent Literature 1: Japanese Patent Application Laid-open No. 2005-79546

SUMMARY

Technical Problem

According to the technique of Patent Literature 1, which is a conventional technique, the number of gaps provided in a magnetic path is limited to up to two. Thus, the conventional technique, in which leakage flux is insufficiently suppressed, has a problem that it is difficult to reduce loss in a coil.

The present invention has been made in view of the above, and its object is to provide a coil apparatus that allows a reduction in loss in a coil.

Solution to Problem

To solve the above problems and achieve the object a coil apparatus according to the present invention includes: a coil;

2

a first core component including a leg around which the coil is wound; and a second core component that includes a plurality of core segments arranged in a row with gaps between the core segments, and is connected to the leg to form a magnetic path together with the first core component.

Advantageous Effects of Invention

The coil apparatus according to the present invention has the effect of allowing a reduction in loss in a coil.

BRIEF DESCRIPTION OF DRAWINGS

FIG. 1 is a circuit diagram illustrating an example of a power converter including a coil apparatus according to a first embodiment of the present invention.

FIG. 2 is a top view of main components constituting the power converter illustrated in FIG. 1.

FIG. 3 is another top view of the main components constituting the power converter illustrated in FIG. 1.

FIG. 4 is an exploded view of the coil apparatus according to the first embodiment.

FIG. 5 is a cross-sectional view of the coil apparatus according to the first embodiment.

FIG. 6 is a top view of the coil apparatus according to the first embodiment.

FIG. 7 is a diagram illustrating a first modification of a core module included in the coil apparatus according to the first embodiment.

FIG. 8 is a diagram illustrating a second modification of the core module included in the coil apparatus according to the first embodiment.

FIG. 9 is a diagram illustrating a third modification of the core module included in the coil apparatus according to the first embodiment.

FIG. 10 is a diagram illustrating a fourth modification of the core module included in the coil apparatus according to the first embodiment.

FIG. 11 is a diagram illustrating a first modification of a case included in the core module illustrated in FIGS. 4 to 6.

FIG. 12 is a diagram illustrating a second modification of a case included in the core module illustrated in FIGS. 4 to 6.

FIG. 13 is a top view of the case illustrated in FIG. 12.

FIG. 14 is a diagram illustrating a third modification of a case included in the core module illustrated in FIGS. 4 to 6.

FIG. 15 is a diagram illustrating a lid attached to the case illustrated in FIG. 14.

FIG. 16 is a diagram illustrating an example of a mechanism for fitting between the case and the lid illustrated in FIG. 14.

FIG. 17 is a diagram illustrating a modification of the case and the lid illustrated in FIG. 14.

FIG. 18 is a diagram illustrating a first example of a configuration for installing the coil apparatus according to the first embodiment.

FIG. 19 is a cross-sectional view illustrating the coil apparatus and the configuration for installing the coil apparatus illustrated in FIG. 18 in an assembled state.

FIG. 20 is a diagram illustrating a second example of a configuration for installing the coil apparatus according to the first embodiment.

FIG. 21 is a diagram illustrating a third example of a configuration for installing the coil apparatus according to the first embodiment.

FIG. 22 is a diagram illustrating a fourth example of a configuration for installing the coil apparatus according to the first embodiment.

FIG. 23 is a diagram illustrating the fourth example of the configuration for installing the coil apparatus according to the first embodiment.

FIG. 24 is a diagram illustrating a first modification of base cores included in the coil apparatus according to the first embodiment.

FIG. 25 is a diagram illustrating a second modification of a base core included in the coil apparatus according to the first embodiment.

FIG. 26 is a diagram illustrating a first example in which two coil units are provided in the coil apparatus according to the first embodiment.

FIG. 27 is a diagram illustrating a second example in which two coil units are provided in the coil apparatus according to the first embodiment.

FIG. 28 is an exploded view of a coil apparatus according to a second embodiment of the present invention.

FIG. 29 is a diagram illustrating an assembled state of the coil apparatus illustrated in FIG. 28.

FIG. 30 is an exploded view of the coil apparatus according to a modification of the second embodiment.

FIG. 31 is an exploded view of a coil apparatus according to a third embodiment of the present invention.

FIG. 32 is a side view illustrating an assembled state of the coil apparatus illustrated in FIG. 31.

FIG. 33 is a top view illustrating the assembled state of the coil apparatus illustrated in FIG. 31.

FIG. 34 is a cross-sectional view of a coil apparatus according to a fourth embodiment of the present invention.

FIG. 35 is a plan view illustrating an example of a surface of a metal housing on which the coil apparatus according to the fourth embodiment is disposed.

FIG. 36 is a plan view illustrating another example of the surface of the metal housing on which the coil apparatus according to the fourth embodiment is disposed.

FIG. 37 is a cross-sectional view of a coil apparatus according to a fifth embodiment of the present invention.

FIG. 38 is a cross-sectional view of a coil apparatus according to a sixth embodiment of the present invention.

FIG. 39 is an enlarged view of a divider included in the coil apparatus illustrated in FIG. 38.

FIG. 40 is a cross-sectional view of a coil apparatus according to a modification of the sixth embodiment.

FIG. 41 is a cross-sectional view of a coil apparatus according to a seventh embodiment of the present invention.

FIG. 42 is an enlarged view illustrating a metal plate as viewed from below, on which the coil apparatus illustrated in FIG. 41 is provided.

FIG. 43 is an enlarged view illustrating the metal plate as viewed from the side, on which the coil apparatus illustrated in FIG. 41 is provided.

FIG. 44 is a cross-sectional view illustrating a coil apparatus according to a first modification of the seventh embodiment during assemblage.

FIG. 45 is a cross-sectional view illustrating an assembled state of the coil apparatus illustrated in FIG. 44.

FIG. 46 is a cross-sectional view of a coil apparatus according to a second modification of the seventh embodiment.

FIG. 47 is an exploded view of a coil apparatus according to an eighth embodiment.

FIG. 48 is a cross-sectional view illustrating an assembled state of the coil apparatus illustrated in FIG. 47.

FIG. 49 is an exploded view of a coil apparatus according to a first modification of the eighth embodiment.

FIG. 50 is an exploded view of a coil apparatus according to a second modification of the eighth embodiment.

FIG. 51 is a cross-sectional view illustrating an assembled state of the coil apparatus illustrated in FIG. 50.

FIG. 52 is an exploded view of a coil apparatus according to a third modification of the eighth embodiment.

FIG. 53 is a cross-sectional view illustrating an assembled state of the coil apparatus illustrated in FIG. 52.

FIG. 54 is an exploded view of a coil apparatus according to a fourth modification of the eighth embodiment.

FIG. 55 is a cross-sectional view illustrating an assembled state of the coil apparatus illustrated in FIG. 54.

FIG. 56 is an exploded view of a coil apparatus according to a fifth modification of the eighth embodiment.

FIG. 57 is a cross-sectional view illustrating an assembled state of the coil apparatus illustrated in FIG. 56.

DESCRIPTION OF EMBODIMENTS

Hereinafter, a coil apparatus and a power converter according to embodiments of the present invention will be described in detail with reference to the drawings. Note that the embodiments are not intended to limit this invention.

First Embodiment

FIG. 1 is a circuit diagram illustrating an example of a power converter including a coil apparatus according to a first embodiment of the present invention. A power converter 100 illustrated in FIG. 1 is an isolated direct current (DC)-DC converter. The power converter 100 converts a DC voltage input to input terminals 101 and 102 into a DC voltage and outputs the DC voltage from output terminals 191 and 192. A high voltage of about 100 V to 600 V supplied from a vehicle-mounted high-voltage battery is input to the input terminals 101 and 102. A voltage of about 12 V to 16 V, which is a power supply voltage of a vehicle-mounted auxiliary system component, is output from the output terminals 191 and 192.

The power converter 100 includes a full-bridge circuit 110, a resonance coil 120, a transformer 130, a secondary-side rectifier circuit 140, and a smoothing circuit 150. The high DC voltage supplied to the input terminals 101 and 102 is input to the full-bridge circuit 110. The full-bridge circuit 110 includes switching elements 111, 112, 113, and 114. Each of the switching elements 111, 112, 113, and 114 is a metal-oxide semiconductor field-effect transistor (MOSFET), an insulated-gate bipolar transistor (IGBT), or the like. The full-bridge circuit 110 operates to generate an AC voltage from the DC voltage by the switching elements 111, 112, 113, and 114. The AC component generated on the input side by the operation of the full-bridge circuit 110 is mainly absorbed by an input capacitor 103. This reduces the occurrence of noise in input lines.

The resonance coil 120 and a primary coil 131 of the transformer 130 are connected in series. The AC voltage generated by the full-bridge circuit 110 is applied to the resonance coil 120 and the primary coil 131. The resonance coil 120 resonates with capacitance components produced by MOSFETs or external capacitors connected in parallel with the switching elements 111, 112, 113, and 114, respectively, to control the losses of the switching elements 111, 112, 113, and 114. In this operation, the resonance coil 120 is required to have accuracy in inductance value, that is, small variations in inductance value.

When the AC voltage is applied to the primary coil 131, an AC voltage depending on the turn ratio of the transformer 130 is generated in secondary coils 132 and 133 of the transformer 130. The AC voltage generated in the secondary coils 132 and 133 is input to the secondary-side rectifier circuit 140. The AC voltage input to the secondary-side rectifier circuit 140 is rectified by rectifier elements 141 and 142 represented by Schottky barrier diodes. Consequently, at a center tap that is a point of connection between the secondary coil 132 and the secondary coil 133, an AC voltage full-wave rectified relative to ground potential is generated.

The smoothing circuit 150 includes a smoothing coil 151 and an output capacitor 152. The AC voltage generated by the transformer 130 is smoothed by the smoothing circuit 150, so that a desired flat DC voltage is generated between the output terminal 191 and the output terminal 192. The smoothing coil 151 used here is required to have good DC superposition characteristics in addition to accuracy in inductance value. The output terminal 192 that is a negative terminal of the output terminals 191 and 192 is not distinctly provided. A metal housing that is a structure serving as grounds (GNDs) 161, 162, and 163 has its function.

FIG. 2 is a top view of main components constituting the power converter illustrated in FIG. 1. FIG. 2 does not illustrate some of the components of the power converter 100. FIG. 2 does not illustrate part of the components.

A metal housing 160 is a housing of the power converter 100. The metal housing 160 is a structure serving as the GNDs 161, 162, and 163 and also serves as a cooler. The input terminals 101 and 102, the input capacitor 103, a control circuit of the switching elements 111, 112, 113, and 114, and a drive circuit are mounted on a printed-circuit board 170.

The resonance coil 120 is required to have small variations in inductance value to adjust resonance frequency. As a core constituting the resonance coil 120, a core in which an E-shaped core and an E-shaped core are combined, or a core having a toroidal shape is typically used. As a soft magnetic material to form a magnetic path, a dust core material such as pure iron or an Fe—Si alloy is used. In the first embodiment, the core constituting the resonance coil 120 is a planar core, and is a ferrite core of Mn—Zn or the like provided with a plurality of gaps. The resonance coil 120, which is provided with the plurality of gaps, can achieve higher performance and can control a height from an installation base as compared with the above-mentioned conventional technique. FIG. 2 does not illustrate a component to which the resonance coil 120 is connected and a configuration for fixing the resonance coil 120 to the metal housing 160.

The transformer 130 is a planar transformer. The primary coil 131 and the secondary coil 132 are a coil unit included in the transformer 130. The transformer 130 includes: an E-shaped core; an I-shaped core; a printed-circuit board on which the primary coil 131 is formed; and a printed-circuit board on which the secondary coil 132 is formed. There are no gaps in a magnetic path formed by the E-shaped core and the I-shaped core. In the secondary-side rectifier circuit 140, the rectifier element 141 and the rectifier element 142 are installed in one package.

The smoothing coil 151 requires a highly accurate inductance value and DC superposition characteristics. As a core constituting the smoothing coil 151, a core in which an E-shaped core and an E-shaped core are combined, or a core having a toroidal shape is typically used, similarly as the case of resonance coil 120. As a soft magnetic material to

form a magnetic path, a dust core material such as pure iron or an Fe—Si alloy is used. In the first embodiment, the core constituting the smoothing coil 151 is a planar core, and is a ferrite core of Mn—Zn or the like provided with a plurality of gaps. The smoothing coil 151, which is provided with the plurality of gaps, can achieve higher performance and can control a height from an installation base as compared with the above-mentioned conventional technique. The coil constituting the smoothing coil 151 is formed on a printed-circuit board. FIG. 2 does not illustrate a component to which the smoothing coil 151 is connected and a configuration for fixing the smoothing coil 151 to the metal housing 160.

In FIG. 2, the resonance coil 120, the smoothing coil 151, and the coil unit of the transformer 130 are configured using separate printed-circuit boards from each other. The resonance coil 120, the smoothing coil 151, and the coil unit of the transformer 130 may be configured using one printed-circuit board.

FIG. 3 is another top view of the main components constituting the power converter illustrated in FIG. 1. In FIG. 3, the resonance coil 120, the smoothing coil 151, and the coil unit of the transformer 130 are configured using one printed-circuit board 170a. The rectifier elements 141 and 142 may be mounted on the printed-circuit board 170a. The entirety of the printed-circuit board 170 and the printed-circuit board 170a may be formed by one printed-circuit board.

The following describes the configuration of the resonance coil 120 and the configuration of the smoothing coil 151 included in the power converter 100. The resonance coil 120 and the smoothing coil 151 are coil apparatuses included in the power converter 100.

FIG. 4 is an exploded view of a coil apparatus according to the first embodiment. FIG. 5 is a cross-sectional view of the coil apparatus according to the first embodiment. FIG. 6 is a top view of the coil apparatus according to the first embodiment. The X axis is a horizontal axis. The Y axis is a vertical axis. The Z axis is an axis in a depth direction. FIG. 5 illustrates an X-Y cross section parallel to the X axis and the Y axis.

A coil apparatus 12 according to the first embodiment includes a base core 7 that is a first core component, a core module 11 that is a second core component, and a coil unit 6. The core module 11 includes: a plurality of core segments 1, 2, and 3 arranged in a row with gaps between them; divider plates 4 that are plates disposed between the core segments 1, 2, and 3; and a case 5 in which the core segments 1, 2, and 3 and the divider plates 4 are accommodated. The core module 11 is an I-shaped core.

The base core 7 is an E-shaped core with three legs. Outer legs 7e are legs formed at both ends of the base core 7 in the X-axis direction. The center leg 7f is a leg formed at the center of the base core 7 in the X-axis direction. The core module 11 is connected to the center leg 7f and the two outer legs 7e so that the base core 7 and the core module 11 form two magnetic paths 9 that are both closed magnetic paths.

The coil unit 6 is configured using a double-layer printed-circuit board made of Flame Retardant Type 4 (FR-4). A wound winding wire pattern is printed on each side of the printed-circuit board. To reduce the current density of current flowing through the coil unit 6, a four-layer printed-circuit board may be used as the coil unit 6 to have a plurality of separate current paths. The coil unit 6 may be configured using an FR-5 base material or a ceramic base material to increase heat resistance. Instead of using a printed-circuit board, the coil unit 6 may use a copper plate

or an aluminum plate having a thickness of about 0.5 mm to 2 mm. An opening is provided in the center of the coil unit 6. The coil unit 6 is installed in the coil apparatus 12 with the center leg 7f passed through the opening. Thus, a coil that is the winding wire patterns printed on the printed-circuit board becomes a state being wound around the center leg 7f.

The area of the ZX plane of the core segments 1 parallel to the Z axis and the X axis is equal to the area of the ZX plane of the outer legs 7e. The area of the YZ plane of the core segments 1 parallel to the Y axis and the Z axis is equal to the area of the ZX plane of the outer legs 7e. The area of the ZX plane of the core segments 1 may be larger than the area of the ZX plane of the outer legs 7e. The area of the YZ plane of the core segments 1 may be larger than the area of the ZX plane of the outer legs 7e.

The area of the ZX plane of the core segment 2 is equal to the area of the ZX plane of the center leg 7f. The area of the YZ plane of the core segment 2 is equal to the area of the ZX plane of the outer legs 7e. The area of the ZX plane of the core segment 2 may be larger than the area of the ZX plane of the center leg 7f. The area of the YZ plane of the core segment 2 may be larger than the area of the ZX plane of the outer legs 7e.

The height of the core segments 3 in the Y-axis direction is the same as the height of the core segments 1 in the Y-axis direction. The depth of the core segments 3 in the Z-axis direction is the same as the depth of the core segments 1 in the Z-axis direction. Here, dimensional differences of about $\pm 3\%$ between the core segments 3 and the core segments 1 due to dimensional tolerances at the time of manufacturing are ignored. The height of the core segments 3 and the height of the core segments 1 being the same includes the case where there are dimensional differences of about $\pm 3\%$. The depth of the core segments 3 and the depth of the core segments 1 being the same includes the case where there are dimensional differences of about $\pm 3\%$. The thickness of the core segments 3 in the X-axis direction is smaller than the thickness of the core segments 1 in the X-axis direction. A soft magnetic material is used as the material of the cores, which are the core segments 1, the core segment 2, the core segments 3, and the base core 7. As the soft magnetic material, an Mn—Zn or Ni—Zn ferrite core material, and a dust core material such as pure iron, an Fe—Si alloy, an Fe—Si—Al alloy, an Ni—Fe alloy, or an Ni—Fe—Mo alloy are used. The cores may be coated with a powder resin for insulation.

For a ferrite core made of a ferrite core material and a dust core made of a dust core material, a powder material is molded by a press and then fired by heat treatment. The material molded by the press shrinks during heat treatment. Thus, the dimensional accuracy decreases as the core size increases. A large core has a longer firing time and a larger loss in a coil than a small core. Two types of ferrite core materials, a general-purpose ferrite core material and a low-loss ferrite core material, are generally known. The low-loss ferrite core material shows tendencies such as a deterioration in dimensional accuracy and an increase in loss more conspicuously. Therefore, a low-loss, large core is more difficult to control firing temperature and tends to have a large loss in the coil, and thus requires a large amount of manufacturing know-how.

The core segments 1, 2, and 3 are each smaller than a one-piece core when the second core component is formed as the one-piece core, and thus are easier to fire than the one-piece core. Further, the core segments 1, 2, and 3 can reduce loss in the coil unit 6 as compared with the one-piece core. By the use of the core segments 1, 2, and 3 in the core

module 11, the core module 11 can be increased in dimensional accuracy and can be reduced in firing time. Either the general-purpose ferrite core material or the low-loss ferrite core material may be used for the core segments 1, 2, and 3. Since both the general-purpose ferrite core material and the low-loss ferrite core material can be used, the number of procurement sources from which the material of the core segments 1, 2, and 3 can be procured increases. Consequently, the procurement of components for manufacturing the core module 11 can be stabilized, and procurement cost can be reduced. Further, the core module 11 can be reduced in loss in the coil unit 6 and improved in quality.

FIG. 7 is a diagram illustrating a first modification of the core module included in the coil apparatus according to the first embodiment. In the first modification illustrated in FIG. 7, the core module 11 is configured using a plurality of the core segments 2 and a plurality of the core segments 3 without using the core segments 1. In the first modification, in which the core segments 1 are not used, the number of types of components is reduced as compared with the case illustrated in FIGS. 4 to 6. The core module 11, which is reduced in the number of types of components as compared with the case illustrated in FIGS. 4 to 6, can be further improved in productivity and can be reduced in manufacturing cost.

FIG. 8 is a diagram illustrating a second modification of the core module included in the coil apparatus according to the first embodiment. In the second modification illustrated in FIG. 8, the core module 11 is configured using a plurality of the core segments 2 without using the core segments 1 and the core segments 3. The core module 11 is composed of the core segments 2 of one type. That is, each of the plurality of core segments 2 included in the core module 11 has the same dimensions. Here, dimensional differences of about $\pm 3\%$ between the core segments 2 due to dimensional tolerances at the time of manufacturing are ignored. The dimensions of each of the plurality of core segments 2 being the same includes the case where there are dimensional differences of about $\pm 3\%$. In the second modification, in which the core segments 1 and the core segments 3 are not used, the number of types of components is reduced as compared with the case illustrated in FIGS. 4 to 6. According to the first modification and the second modification, the core module 11 is reduced in the number of types of components, and thus can be improved in productivity and reduced in manufacturing cost.

In FIGS. 7 and 8, the width of the core segments 2 in the X-axis direction is larger than the width of the legs of the base core 7 in the X-axis direction. The core segments 2 located above the legs are disposed to protrude from the legs in the X-axis direction. That is, the area of the surfaces of the core segments 2 connected to the legs is larger than the area of the surfaces of the legs connected to the core segments 2. Consequently, the coil apparatus 12 can reduce leakage flux in gaps between the legs and the core segments 2. The width of the core segments 2 in the X-axis direction may be the same as the width of the legs of the base core 7 in the X-axis direction. The area of the surfaces of the core segments 2 connected to the legs may be the same as the area of the surfaces of the legs connected to the core segments 2. Also in this case, the coil apparatus 12 can reduce leakage flux in gaps between the legs and the core segments 2.

The core module 11 may use core segments having a smaller width in the X-axis direction than the core segments 3. FIG. 9 is a diagram illustrating a third modification of the core module included in the coil apparatus according to the first embodiment. In the third modification illustrated in

FIG. 9, the core module 11 is configured using a plurality of sheet-shaped core segments 3b having a smaller width in the X-axis direction than the core segments 3, in place of the core segments 3. The core module 11 can distribute core gaps in the magnetic paths 9 among more gaps as compared with the case illustrated in FIGS. 4 to 6. According to the third modification, the core module 11 can reduce loss in the coil unit 6 by the reduction of leakage flux.

As the core segments 3b, a low-loss ferrite core used in a small planar transformer can be used. Such a ferrite core is distributed in large quantities in the market, and thus is low-cost and easy to procure. The core module 11, in which the core segments 3b are used, can be stabilized in component procurement and reduced in cost.

The core module 11 may be changed in the dimensions of the core segments 1, 2, and 3 from those illustrated in FIGS. 4 to 6. The dimensions of the core segments 1, 2, and 3 constituting the core module 11 are not specified dimensions, and may be various dimensions. FIG. 10 is a diagram illustrating a fourth modification of the core module included in the coil apparatus according to the first embodiment. In the fourth modification illustrated in FIG. 10, the core module 11 includes a plurality of core segments 1a, 2a, and 3a. The height of the core segments 1a, 2a, and 3a in the Y-axis direction is higher than the height of the core segments 1, 2, and 3 in the Y-axis direction. The advantages of the configuration illustrated in FIG. 10 will be described later. The thickness of the core segments 1a, 2a, and 3a in the Y-axis direction, which is the height direction, is larger than the thickness of thin-walled portions of the base core 7. In the base core 7, the thin-walled portions are the outer legs 7e illustrated in FIG. 4. In the configurations illustrated in FIGS. 7 and 8, the core segments 2a and 3a as in the fourth modification may be provided instead of the core segments 2 and 3.

Next, the case 5 and the divider plates 4 illustrated in FIGS. 4 to 6 will be described. The divider plates 4 separate adjacent core segments of the plurality of core segments 1, 2, and 3 from each other. The case 5 holds the plurality of core segments 1, 2, and 3 and the plurality of divider plates 4. The case 5 includes the divider plates 4 that are components formed separately from the case 5.

The case 5 has an I shape that allows the plurality of core segments 1, 2, and 3 to be aligned in the X-axis direction. The divider plates 4 divide the interior of the case 5 to form, with the case 5, spaces in which the core segments 1, 2, and 3 are disposed separately. The divider plates 4 may be of any size as long as they fit in the case 5. The area of the YZ plane of the divider plates 4 is equal to the area of the case 5 in the Y- and Z-directions or about half the area of the case 5 in the Y- and Z-directions. Gaps are formed in the magnetic paths 9 by the divider plates 4 and the case 5. In the following description, the gaps formed in the magnetic paths 9 may be referred to as core gaps.

The length of each core gap in the direction of the magnetic paths 9 is set so that the sum total gap length agrees with a length determined by design. The sum total gap length is the length of the core gaps in the direction of the magnetic paths 9 that is the sum of the lengths of all the core gaps provided at the base core 7 and the core module 11. Core gaps with the Y-axis direction as the length direction are formed between the core module 11 and the outer legs 7e and between the core module 11 and the center leg 7f. Core gaps with the X-axis direction as the length direction are formed in the core module 11.

The relative magnetic permeability of a ferrite core is about 1500 to 4000. The sum total length of the core gaps is

set to about 1 mm to 30 mm. The sum total length of the core gaps is adjusted so that a desired inductance value is obtained. Magnetic flux leaking from the core gaps can interlink with the coil unit 6 disposed adjacent to the core gaps, inducing eddy currents in the coil unit 6. Eddy currents flowing through the coil unit 6 cause loss in the coil unit 6. Leakage flux is reduced by reducing length per core gap. Specifically, the length of each core gap is desirably 1 mm or less. The divider plates 4 and the case 5 use a thin-walled material that can provide core gaps of such a length.

A non-magnetic material such as a resin is used as the material of the divider plates 4 and the case 5. Among resins, a liquid crystal polymer (LCP) or the like is suitable as the material of the divider plates 4 and the case 5. The LCP can form a thin wall of about 0.5 mm, has good dimensional accuracy, and is suitable for processing of complicated shapes, and thus is suitable as the material of the divider plates 4 and the case 5. The LCP has excellent heat resistance. Even when the core temperature reaches a high temperature of about 120 degrees Celsius, the LCP does not cause changes such as softening. Since the divider plates 4 and the case 5 are thin-walled, the amount of the material used in the processing of the divider plates 4 and the case 5 is reduced accordingly. Consequently, even when the LCP, which is expensive among resins, is used, the core module 11 can prevent an increase in cost. As a resin, other than the LCP, polyethylene terephthalate (PET), polybutylene terephthalate (PBT), polypropylene (PP), polyphenylene sulfide (PPS), or the like may be used.

Injection molding is used as a method for processing the divider plates 4 and the case 5. Injection molding is excellent in cost and dimensional accuracy, and is also suitable for processing of complicated shapes. As a method for processing the divider plates 4 and the case 5, extrusion molding, compression molding, or additional processing by a 3D printer may be used.

Of the case 5, portions between the core segments 1 and the outer legs 7e and a portion between the core segment 2 and the center leg 7f are portions to form core gaps, and thus are desirably thin-walled. On the other hand, the other portions of the case 5 are not portions to form core gaps, and thus do not need to be thin-walled. Portions of the case 5 other than portions to form core gaps may be formed with a thickness that can secure the strength of the case 5.

FIG. 11 is a diagram illustrating a first modification of a case included in the core module illustrated in FIGS. 4 to 6. A case 5a of the first modification illustrated in FIG. 11 includes the divider plates 4 in the case 5a. That is, the case 5a is a component molded in one piece including the divider plates 4. The core segments 1, 2, and 3 are disposed between the divider plates 4, separately. In this case, it is not necessary to purchase a mold for processing the divider plates 4 in addition to a mold for processing the case 5a. Thus, the core module 11 can reduce manufacturing cost.

The core module 11 only needs to be able to provide a desired gap length, and the case 5 need not be provided with the divider plates 4. FIG. 12 is a diagram illustrating a second modification of a case included in the core module illustrated in FIGS. 4 to 6. FIG. 13 is a top view of the case illustrated in FIG. 12. A case 5b of the second modification illustrated in FIGS. 12 and 13 includes ribs 13 for positioning each of the plurality of core segments 1, 2, and 3 in the X-axis direction, in place of the divider plates 4 included in the case 5a illustrated in FIG. 11. The core segments 1, 2, and 3 are disposed between the ribs 13, separately. Also in this case, since it is not necessary to purchase a mold for processing the divider plates 4, the core module 11 can

11

reduce manufacturing cost. Further, the amount of material required to form the ribs **13** is smaller than the amount of material required to form the divider plates **4**, and thus the case **5b** can reduce manufacturing cost as compared with the case **5a** provided with the divider plates **4**. For the case **5a** illustrated in FIG. 11, the larger the case **5a**, the more likely portions of the case **5a** where the divider plates **4** are provided are to be warped. Since the case **5b** is not provided with the divider plates **4**, such warpage does not occur.

In the first embodiment, the core module **11**, in which the core segments **1**, **2**, and **3** are disposed in the case **5**, holds the core segments **1**, **2**, and **3** together by the case **5**. Therefore, an increase in the number of core segments **1**, **2**, and **3** provided in the core module **11** rarely leads to a deterioration in the productivity of the core module **11**. In the core module **11**, the core segments **1**, **2**, and **3** are inserted into the spaces into which the interior of the case **5** is divided, to be held. No adhesive is used to hold the core segments **1**, **2**, and **3**. Thus, the core module **11** can eliminate the concern that cracks may occur in the core segments **1**, **2**, and **3** due to the difference in the coefficient of linear expansion between the core segments **1**, **2**, and **3** and an adhesive.

During the production of the core module **11**, the sum total gap length may vary due to the dimensional tolerances of the plurality of core segments **1**, **2**, and **3**, the divider plates **4**, and the case **5**. Variations in the sum total gap length affect variations in inductance value. Such dimensional tolerances generally have a normal distribution. The core module **11** is provided with the plurality of core segments **1**, **2**, and **3** and the divider plates **4**. It is statistically impossible that all of them have a large error of, for example, $\pm 3\sigma$ to $\pm 6\sigma$ with respect to average dimensions. As the number of core segments **1**, **2**, and **3** and the number of divider plates **4** provided in the core module **11** increase, the sum total gap length approaches the sum total gap length when the dimensions are average values. Therefore, the core module **11**, in which a core is divided into the plurality of core segments **1**, **2**, and **3**, can reduce variations in the sum total gap length, and can increase the accuracy of the inductance value.

The above content will be quantitatively explained using a core as an example. The dimensions of a core have percentage errors. If an average dimension is 150 mm and the dimensional tolerance of an unpolished core is 1%, the dimensional tolerance is ± 1.5 mm. For a 30-mm core segment **3**, the 1%-dimensional tolerance is ± 0.3 mm. When a 150-mm core is formed using five 30-mm core segments **3**, a dimensional tolerance of ± 0.3 mm, which is 1% of 30 mm, takes the square root of sum of squares of the five core segments **3**. Thus, for the total length of the five core segments **3**, the dimensional tolerance can be reduced to ± 0.67 mm. This corresponds to 45% of the dimensional tolerance of the 150-mm core, and the dimensional tolerance can be reduced by 55%. Likewise, when a 150-mm core is formed using ten 15-mm core segments **3**, the dimensional tolerance of the total length of the ten core segments **3** is ± 0.47 mm. This corresponds to 32% of the dimensional tolerance of the 150-mm core, and the dimensional tolerance can be reduced by 68%.

Thus, the coil apparatus **12** can reduce variations in inductance value as the number of divisions of the core forming the magnetic paths **9** is increased. The coil apparatus **12** can eliminate the need for core polishing, which has conventionally been performed to reduce dimensional tolerances, and thus allows a reduction in the processing time of the core module **11** and a reduction in manufacturing cost.

12

Even if the core segments **1**, **2**, and **3** are displaced in the X-axis direction in the case **5**, the sum total gap length does not change in the core module **11**. Thus, even when the core segments **1**, **2**, and **3** are not fixed to the case **5** by an adhesive or the like, the coil apparatus **12** can reduce variations in inductance value, and can obtain stable electrical characteristics. The displacement of the core segments **1**, **2**, and **3** in the Z-axis direction hardly affects the inductance value if it is a displacement of about a dimensional tolerance of the case **5**.

The coil apparatus **12** can reduce length per core gap as the number of core gaps increases. By shortening the core gaps, the coil apparatus **12** can reduce magnetic flux leaking from the core gaps, and can reduce eddy-current loss in the coil unit **6** disposed adjacent to the core module **11**. As a result, the coil apparatus **12** can suppress the amount of heat generation. The power converter **100** can improve power efficiency.

A ferrite core is vulnerable to shock and thus can be chipped or cracked by shock. In the first embodiment, all of the core segments **1**, **2**, and **3** are accommodated in the case **5**, so that the coil apparatus **12** can protect the core segments **1**, **2**, and **3** from vibration or shock. The coil apparatus **12** can reduce damage to the core segments **1**, **2**, and **3**. If any of the core segments **1**, **2**, and **3** is chipped and a broken piece is produced, the broken piece having conductivity is kept in the case **5** since the core segments **1**, **2**, and **3** are disposed in the case **5**. Thus, the power converter **100** can prevent a short-circuit failure due to the entry of a broken piece into the printed-circuit board **170** or the switching elements **111**, **112**, **113**, and **114**.

A lid may be provided on the top of the case **5**. FIG. 14 is a diagram illustrating a third modification of a case included in the core module illustrated in FIGS. 4 to 6. To a case **5c** of the third modification illustrated in FIG. 14, a lid **8** is attached which covers the upper part of the spaces in which the core segments **1**, **2**, and **3** are accommodated. FIG. 14 illustrates the case **5c**, the core segments **1**, **2**, and **3**, and the lid **8** in a disassembled state. The case **5c** is the case **5a** illustrated in FIG. 11 to which a mechanism for fitting with the lid **8** is added.

FIG. 15 is a diagram illustrating the lid attached to the case illustrated in FIG. 14. FIG. 16 is a diagram illustrating an example of the mechanism for fitting between the case and the lid illustrated in FIG. 14. The lid **8** and the case **5c** are provided with the mechanism of a snap-fit shape or the like to increase fitting strength.

By the provision of the lid **8** on the case **5c**, if any of the core segments **1**, **2**, and **3** is damaged, the coil apparatus **12** can prevent a broken piece produced by the damage from flying to the outside of the case **5c**. Further, by the mechanism for increasing the fitting strength provided to the lid **8** and the case **5c**, the core module **11** can increase the strength of fixing the core segments **1**, **2**, and **3**. Consequently, the core module **11** can improve vibration resistance. The lid **8** may be attached to the case **5** illustrated in FIGS. 4 to 6, or may be attached to the case **5b** illustrated in FIG. 12.

FIG. 17 is a diagram illustrating a modification of the case and the lid illustrated in FIG. 14. An opening **17** is formed in the top surface of the lid **8** illustrated in FIG. 17. An opening **18** is formed in each of the four side surfaces of the case **5c** illustrated in FIG. 17. Heat inside the case **5c** with a state the lid **8** attached is released to the outside of the case **5c** through the openings **17** and **18**. Consequently, the coil apparatus **12** can be improved in heat dissipation. The provision of the openings **17** and **18** allows a reduction in the amount of the material used to manufacture the lid **8** and the

13

case 5c. The positions, shapes, and numbers of the openings 17 and 18 can be set as desired so as to prevent the core segments 1, 2, and 3 in the case 5c from passing through the openings 17 and 18 and falling off. Suffice for the case 5c and the lid 8 to have at least the opening 17 in the lid 8 or the openings 18 in the case 5c.

FIG. 18 is a diagram illustrating a first example of a configuration for installing the coil apparatus according to the first embodiment. The coil apparatus 12 is installed in the metal housing 160 with the base core 7 in contact with the metal housing 160. Heat-conductive grease or a heat dissipation sheet may be sandwiched between the base core 7 and the metal housing 160. The metal housing 160 has a configuration for fixing the coil apparatus 12 and also serves as a cooler. The coil apparatus 12 is assembled with the base core 7 thermally coupled to the metal housing 160. This allows the coil apparatus 12 to be cooled using the metal housing 160.

A metal plate 160a is a plate material that covers the upper part of the coil apparatus 12. Two metal blocks 160b are columnar structures that support the metal plate 160a on the metal housing 160. The metal blocks 160b are erected at positions adjacent to the coil apparatus 12 in the X-axis direction in the metal housing 160. Screws 10 fix the metal plate 160a and the metal blocks 160b to the metal housing 160. The configuration for installing the coil apparatus 12 includes the metal housing 160, the metal plate 160a, and the metal blocks 160b.

FIG. 19 is a cross-sectional view illustrating the coil apparatus and the configuration for installing the coil apparatus illustrated in FIG. 18 in an assembled state. The metal plate 160a has a configuration for fixing the coil apparatus 12, and also serves as a cooler. The coil apparatus 12 is assembled with the core module 11 thermally coupled to the metal plate 160a. This allows the coil apparatus 12 to be cooled using the metal plate 160a.

Heat generated in the base core 7 is mainly transferred to the metal housing 160. Heat generated in the core module 11 is mainly transferred to the metal plate 160a. The heat transferred to the metal plate 160a is transferred to the metal housing 160 via the metal blocks 160b. Arrows illustrated in FIG. 19 illustrate how the heat is transferred. The coil apparatus 12, in which the base core 7 and the core module 11 are thermally joined to the coolers, separately, can accelerate heat dissipation from the coil apparatus 12.

The metal plate 160a and the metal blocks 160b illustrated in FIGS. 18 and 19 are separate components. The coil apparatus 12 may be fixed by one structure made of a metal material instead of by the metal plate 160a and the metal blocks 160b. FIG. 20 is a diagram illustrating a second example of a configuration for installing the coil apparatus according to the first embodiment. A metal structure 160c according to the second example is provided in place of the metal plate 160a and the metal blocks 160b. The metal structure 160c has the same shape as the combination of the metal plate 160a and the metal blocks 160b, and has a U shape. Also in this case, the coil apparatus 12 is fixed to be able to accelerate heat dissipation.

The metal structure 160c may be provided with radiating fins 166. FIG. 21 is a diagram illustrating a third example of a configuration for installing the coil apparatus according to the first embodiment. A metal structure 160g according to the third example is the metal structure 160c with the radiating fins 166 added to the top surface. By fixing the coil apparatus 12 with the metal structure 160g provided with the radiating fins 166, heat dissipation from the coil apparatus

14

12 is further accelerated. Radiating fins may be added to the top surface of the metal plate 160a described above.

FIGS. 22 and 23 are diagrams illustrating a fourth example of a configuration for installing the coil apparatus according to the first embodiment. FIGS. 22 and 23 illustrate a configuration example when it is not necessary to transfer the heat of the core module 11 to the metal housing 160. In the fourth example, a metal spring 14 for fixing the coil apparatus 12 to the metal housing 160 is provided. FIG. 22 illustrates the metal spring 14 when being attached to the metal housing 160. FIG. 23 illustrates a state the metal spring 14 is attached to the metal housing 160. FIGS. 22 and 23 illustrate the side faces of the metal spring 14 and screws 10a, and the cross sections of components other than the metal spring 14 and the screws 10a.

The metal spring 14 is a metal plate of about 0.1 mm to 1 mm in thickness and has elasticity. The metal spring 14 is fixed to the metal housing 160 by the screws 10a. The metal spring 14 is provided with projections 14a for fixing the position of the core module 11 in the Z-axis direction. The coil apparatus 12 is fixed in a state of being pressed against the metal housing 160 by the elasticity of the metal spring 14. The coil apparatus 12 is limited in displacement in the Z-axis direction by the projections 14a to be fixed in position in the metal housing 160.

A typical example of the case where it is not necessary to transfer the heat of the core module 11 to the metal housing 160 is the case where a low-loss ferrite core is used as the core segments 1a, 2a, and 3a as illustrated in FIG. 10. By using the low-loss ferrite core, the coil apparatus 12 can reduce loss in the core segments 1a, 2a, and 3a. The size of the core segments 1a, 2a, and 3a in the Y-axis direction is set so as to increase the cross-sectional area of the magnetic paths 9 in the range of about one to two times compared with a case the core segments 1, 2, and 3 are used. The coil apparatus 12 can reduce loss in the core module 11 and reduce the amount of heat generation and the density of heat generation in the core module 11, and can suppress a temperature rise in the core module 11. The configuration illustrated in FIG. 10 eliminates the need to cool the core module 11 by placing the core module 11 in contact with the metal plate 160a or the metal structure 160c or 160g. Thus, in the configuration illustrated in FIG. 10, the coil apparatus 12 can be fixed using the metal spring 14. The metal spring 14 can be easily manufactured by bending thin sheet metal. By using the metal spring 14, the power converter 100 allows a reduction in manufacturing cost and reductions in the size and weight of the power converter 100.

The coil apparatus 12 may include a base core 7 other than the E-shaped core. FIG. 24 is a diagram illustrating a first modification of base cores included in the coil apparatus according to the first embodiment. In the first modification illustrated in FIG. 24, the coil apparatus 12 includes two base cores 7c that are U-shaped cores, instead of the E-shaped base core 7. Each U-shaped core has two legs. The shape of the base cores 7c is a shape that can be obtained by dividing the E-shaped base core 7 at the center in the X-axis direction.

FIG. 25 is a diagram illustrating a second modification of a base core included in the coil apparatus according to the first embodiment. In the second modification illustrated in FIG. 25, the coil apparatus 12 includes one base core 7d that is a U-shaped core, instead of the E-shaped base core 7. The coil unit 6 is installed in the coil apparatus 12 with one leg of the base core 7d passed through the opening of the coil unit 6.

15

The coil apparatus **12** may include two or more coil units **6**. FIG. **26** is a diagram illustrating a first example in which two coil units are provided in the coil apparatus according to the first embodiment. In the first example illustrated in FIG. **26**, two coil units **6** are provided at one base core **7d** that is a U-shaped core. One of the two coil units **6** is installed in the coil apparatus **12** with one leg of the base core **7d** passed through the opening of the coil unit **6**. The other of the two coil units **6** is installed in the coil apparatus **12** with the other leg of the base core **7d** passed through the opening of the coil unit **6**. The two coil units **6** are adjacent to each other in the X- and Z-directions.

FIG. **27** is a diagram illustrating a second example in which two coil units are provided in the coil apparatus according to the first embodiment. In the second example illustrated in FIG. **27**, two coil units **6** are provided at one base core **7c** that is a U-shaped core. One of the two coil units **6** is installed in the coil apparatus **12** with one leg of the base core **7c** passed through the opening of the coil unit **6**. The other of the two coil units **6** is installed in the coil apparatus **12** with the other leg of the base core **7c** passed through the opening of the coil unit **6**. A part of one coil unit **6** and a part of the other coil unit **6** are adjacent to each other in the Y-axis direction.

The circuit configuration of the power converter **100** is not limited to that illustrated in FIG. **1**, and may be a circuit of a system different from that of the circuit illustrated in FIG. **1**. The power converter **100** is not limited to that including the resonance coil **120**, the smoothing coil **151**, and the transformer **130**, and may be that including at least one of the single resonant coil **120**, the single smoothing coil **151**, and the single transformer **130**. The transformer **130** includes one or more coil units **6**. The resonance coil **120** and the smoothing coil **151** may also include one or more coil units **6**.

According to the first embodiment, the core module **11** includes the plurality of core segments **1**, **2**, and **3** arranged in a row with gaps between them, so that the coil apparatus **12** can easily distribute gaps in the magnetic paths **9**. By distributing gaps, the coil apparatus **12** can reduce length per gap, and can reduce leakage flux in the gaps. By the reduction of leakage flux, the coil apparatus **12** can reduce loss in the coil unit **6**. Thus, the coil apparatus **12** has the effect of being able to reduce loss in the coil unit **6**.

The coil apparatus **12** can use a low-loss ferrite core as the core segments **1**, **2**, and **3**, and thus can further reduce loss in the coil unit **6**. As compared with conventional techniques, the coil apparatus **12** can reduce the tolerance of the inductance value during the production of the coil apparatus **12**. The coil apparatus **12** can be easily assembled, allowing an improvement in productivity. The coil apparatus **12** eliminates the need for core polishing, allowing a reduction in core procurement cost. A reduction in the production cost of the coil apparatus **12** allows a reduction in the production cost of the power converter **100**. The thermal coupling between the coil apparatus **12** and the metal housing **160** allows the power converter **100** to efficiently cool the coil apparatus **12**, allowing a reduction in the size of the power converter **100**.

Second Embodiment

FIG. **28** is an exploded view of a coil apparatus according to a second embodiment of the present invention. FIG. **29** is a diagram illustrating an assembled state of the coil apparatus illustrated in FIG. **28**. A case **5d** included in a coil apparatus **12a** according to the second embodiment have

16

projections **5g** for positioning a core module **11a** relative to the base core **7**. In the second embodiment, the same reference numerals are assigned to the same components as those in the first embodiment, and a configuration different from that of the first embodiment will be mainly described.

The case **5d** is the case **5a** illustrated in FIG. **11** to which the projections **5g** are added. The projections **5g** provided to the case **5d** are ribs. The projections **5g** are provided to extend downward at the four corners of the case **5d** in the ZX plane. By the provision of the projections **5g** to the case **5d**, the coil apparatus **12a** allows the positioning of the core module **11a** and the base core **7** in the X-axis direction and the Z-axis direction. Thus, the coil apparatus **12a** can facilitate assembly. Further, by the provision of the projections **5g** to the case **5d**, the coil apparatus **12a** can prevent a misalignment between the core module **11a** and the base core **7** in the X-axis direction and the Z-axis direction. The projections **5g** may be attached to any of the case **5** illustrated in FIGS. **4** to **6**, the case **5b** illustrated in FIG. **12**, the case **5c** illustrated in FIG. **15**, and the case **5c** illustrated in FIG. **17**.

FIG. **30** is an exploded view of the coil apparatus according to a modification of the second embodiment. A case **5f** included in the coil apparatus **12a** has four outer walls extending downward so as to be able to cover the periphery of the base core **7**. Also in the modification, the coil apparatus **12a** allows the positioning of the core module **11a** and the base core **7**, and thus can facilitate assembly. The coil apparatus **12a** can prevent a misalignment between the core module **11a** and the base core **7** in the X-axis direction and the Z-axis direction.

According to the second embodiment, the coil apparatus **12a** can provide the same effects as those of the first embodiment, and is provided with the case **5d** or the case **5f** to be able to facilitate assembly and prevent a misalignment between the core module **11a** and the base core **7**.

By the provision of the case **5d** or the case **5f** in the coil apparatus **12a**, the power converter **100** can prevent a misalignment between the core module **11a** and the base core **7** when vibration or shock is applied to the power converter **100**. The coil apparatus **12a** can maintain electrical characteristics by preventing a misalignment between the core module **11a** and the base core **7**. The power converter **100** can be improved in quality since the electrical characteristics of the coil apparatus **12a** can be maintained.

Third Embodiment

FIG. **31** is an exploded view of a coil apparatus according to a third embodiment of the present invention. FIG. **32** is a side view illustrating an assembled state of the coil apparatus illustrated in FIG. **31**. FIG. **33** is a top view illustrating the assembled state of the coil apparatus illustrated in FIG. **31**. A case **5e** included in a coil apparatus **12b** according to the third embodiment has projections **5i** formed by extending outer walls of the case **5e** downward. At the distal ends of the projections **5i**, fixing portions **5h** are provided for fixing the case **5e** to the metal housing **160**, which is a structure in which the coil apparatus **12b** is installed. In the third embodiment, the same reference numerals are assigned to the same components as those in the first and second embodiments, and a configuration different from that of the first and second embodiments will be mainly described.

The case **5e** is made by adding projections **5i** to the case **5c** illustrated in FIG. **14**. The projections **5i** are formed by extending downward outer walls that are end surfaces of the case **5e** in the X-axis direction. The fixing portions **5h** come

into contact with the metal housing 160. The fixing portions 5h are provided at the four corresponding corners of the case 5e in the X-axis direction and the Z-axis direction. A hole of a diameter of about 3 mm to 6 mm is formed in each of the fixing portions 5h. By tightening the screws 10a passed through the holes into the metal housing 160, the coil apparatus 12b is fixed to the metal housing 160. Although FIG. 31 illustrates the coil apparatus 12b with the lid 8, the coil apparatus 12b may not have the lid 8.

According to the third embodiment, as in the second embodiment, by including the case 5e, the coil apparatus 12b can facilitate assembly and prevent a misalignment between the core module 11b and the base core 7. The coil apparatus 12b, which can be fixed to the metal housing 160 by the case 5e, eliminates the need to additionally provide a configuration for fixing to the metal housing 160. The power converter 100 can have a simpler configuration than when a configuration for the coil apparatus 12b to the metal housing 160 is additionally required. In the coil apparatus 12b with the lid 8, the projections 5i and the fixing portions 5h may be provided to the lid 8 instead of to the case 5e. The projections 5i and the fixing portions 5h may be attached to any of the case 5 illustrated in FIGS. 4 to 6, the case 5b illustrated in FIG. 12, the case 5c illustrated in FIG. 15, and the case 5c illustrated in FIG. 17.

Fourth Embodiment

FIG. 34 is a cross-sectional view of a coil apparatus according to a fourth embodiment of the present invention. In a coil apparatus 12c according to the fourth embodiment, the E-shaped base core 7 illustrated in FIGS. 4 to 6 is divided into a plurality of core components aligned with gaps between them. In the fourth embodiment, the same reference numerals are assigned to the same components as those in the first to third embodiments, and a configuration different from that of the first to third embodiments will be mainly described.

In the fourth embodiment, a first core component consists of a plurality of core components that is two base cores 7a and one base core 7b. The base core 7b is disposed in the center of the coil apparatus 12c in the X-axis direction. The base cores 7a are adjacent to the base core 7b in the X-axis direction. Gaps are provided between the base cores 7a and the base core 7b. Thermal coupling between the base cores 7a and 7b and the metal housing 160 is provided as is the case with the base core 7.

By the provision of the gaps between the base cores 7a and the base core 7b, the coil apparatus 12c can provide much more gaps in the magnetic paths 9 than in the case illustrated in FIGS. 4 to 6. If the number of gaps in the magnetic paths 9 is insufficient in the configuration illustrated in FIGS. 4 to 6, the coil apparatus 12c can provide a sufficient number of gaps by the provision of the gaps between the base cores 7a and 7b.

FIG. 35 is a plan view illustrating an example of a surface of the metal housing on which the coil apparatus according to the fourth embodiment is disposed. Grooves 15 having a depth of about 1 mm to 2 mm is provided on the surface of the metal housing 160 on which the coil apparatus 12c is disposed. The metal housing 160 is provided with three grooves 15. One of the three grooves 15 has the same shape as the base core 7b in the X-axis direction and the Z-axis direction. The base core 7b is fitted into this groove 15. The other two of the three grooves 15 have the same shape as the base cores 7a in the X-axis direction and the Z-axis direction. The base cores 7a are fitted into the two corresponding

grooves 15. Thus, the base cores 7a and the base core 7b can be positioned to form gaps of a predetermined length between the base cores 7a and the base core 7b. Further, the length of the gaps between the base cores 7a and the base core 7b can be kept constant.

FIG. 36 is a plan view illustrating another example of the surface of the metal housing on which the coil apparatus according to the fourth embodiment is disposed. Ribs 16 having a height of about 1 mm to 2 mm are provided on the surface of the metal housing 160 on which the coil apparatus 12c is disposed. One of three regions enclosed by the ribs 16 has the same shape as the base core 7b in the X-axis direction and the Z-axis direction. The base core 7b is fitted into this region. The other two of the three regions have the same shape as the base cores 7a in the X-axis direction and the Z-axis direction. The base cores 7a are fitted into the two corresponding regions. Thus, the base cores 7a and the base core 7b can be positioned to form gaps of a predetermined length between the base cores 7a and the base core 7b. Further, the length of the gaps between the base cores 7a and the base core 7b can be kept constant.

According to the fourth embodiment, by the provision of the base cores 7a and 7b, the coil apparatus 12c can increase the number of gaps provided in the magnetic paths 9. Consequently, the coil apparatus 12c can further reduce loss in the coil unit 6.

Fifth Embodiment

FIG. 37 is a cross-sectional view of a coil apparatus according to a fifth embodiment of the present invention. In a coil apparatus 12d according to the fifth embodiment, the base core 7b illustrated in FIG. 34 is divided into two base cores 7a. That is, in the coil apparatus 12d, the E-shaped base core 7 illustrated in FIGS. 4 to 6 is divided into four base cores 7a aligned with gaps between them. In the fifth embodiment, the same reference numerals are assigned to the same components as those in the first to fourth embodiments, and a configuration different from that of the first to fourth embodiments will be mainly described.

In the fifth embodiment, a first core component consists of the four base cores 7a, which are a plurality of core components. The four base cores 7a are formed from core components of one type. The four base cores 7a have the same shape. Here, dimensional differences of about $\pm 3\%$ between the base cores 7a due to dimensional tolerances at the time of manufacturing are ignored. The plurality of base cores 7a having the same shape includes the case where there are dimensional differences of about $\pm 3\%$. Gaps are provided between the base cores 7a. By the provision of the gaps between the base cores 7a, the coil apparatus 12d can provide much more gaps in the magnetic paths 9 than in the case illustrated in FIGS. 4 to 6.

The size of a core component installed in the power converter 100 increases in proportion to electric power. The upper limit of the size of the core component that can be manufactured is limited by the size of core manufacturing equipment such as a press or a firing machine. If the coil apparatus 12d is provided with the first core component that is a one-piece core component instead of the four base cores 7a, the maximum size of the first core component is determined by the size of the core manufacturing equipment. In the fifth embodiment, in which the first core component is divided into the four base cores 7a, each of the four base cores 7a can be increased in size to the maximum size. Consequently, the size of the first core component provided in the coil apparatus 12d can be up to four times the size of

the first core component that is a one-piece core component. Thus, even if core manufacturing equipment larger than existing core manufacturing equipment is not used in the manufacturing of the first core component, the coil apparatus **12d** including the first core component up to four times as large as the first core component formed of a one-piece core component can be manufactured.

As in the fourth embodiment, the metal housing **160** may be provided with the grooves **15** or the ribs **16** for positioning the base cores **7a**. This allows the base cores **7a** to be positioned to form gaps of a predetermined length between the base cores **7a**. Further, the gap length between the base cores **7a** can be kept constant.

According to the fifth embodiment, by the provision of the plurality of base cores **7a**, the coil apparatus **12d** can increase the number of gaps provided in the magnetic paths **9**. Consequently, the coil apparatus **12d** can further reduce loss in the coil unit **6**.

Sixth Embodiment

FIG. 38 is a cross-sectional view of a coil apparatus according to a sixth embodiment of the present invention. In a coil apparatus **12e** according to the sixth embodiment, adjacent core segments of the plurality of core segments **1**, **2**, and **3** are bonded to each other with a divider **4b** interposed between them. In the sixth embodiment, the same reference numerals are assigned to the same components as those in the first to fifth embodiments, and a configuration different from that of the first to fifth embodiments will be mainly described.

FIG. 39 is an enlarged view of a divider included in the coil apparatus illustrated in FIG. 38. The divider **4b** includes a divider plate **4** that is a plate material. Double-sided adhesive tapes **4a** having high adhesive strength are stuck to both sides of the divider plate **4**. By sticking the core segments **1**, **2**, and **3** to the double-sided adhesive tapes **4a**, the dividers **4b** bond adjacent core segments of the core segments **1**, **2**, and **3** to each other. Gaps are formed between adjacent core segments of the core segments **1**, **2**, and **3** by the provision of the dividers **4b**.

By the bonding of the core segments **1**, **2**, and **3** to each other, the core segments **1**, **2**, and **3** are fixed in a core module **11c**. Since the core segments **1**, **2**, and **3** are fixed by the dividers **4b**, it is not necessary to provide the case **5** in the coil apparatus **12e** for fixing the core segments **1**, **2**, and **3**. In this case, the manufacturing cost of the case **5** and a mold for processing the case **5** are unnecessary, so that the core module **11c** can reduce manufacturing cost. Further, the coil apparatus **12e** can eliminate gaps between the base core **7** and the core module **11c**. The coil apparatus **12e** can eliminate leakage flux from between the base core **7** and the core module **11c**, and thus can further reduce loss in the coil unit **6**.

FIG. 40 is a cross-sectional view of a coil apparatus according to a modification of the sixth embodiment. In a coil apparatus **12f**, adjacent core segments of the core segments **1**, **2**, and **3** constituting a core module **11d** are bonded to each other with an adhesive **4c** interposed between them. Glass beads are blended into the adhesive **4c**. By the addition of the glass beads to the adhesive **4c**, adjacent core segments of the core segments **1**, **2**, and **3** are bonded to each other with a certain spacing maintained between them. Thus, gaps are formed between adjacent core segments of the core segments **1**, **2**, and **3** by the provision of the adhesive **4c**. Also in this modification, the core module **11d** eliminates the need for the case **5**, allowing a

reduction in manufacturing cost. The coil apparatus **12f** can eliminate leakage flux from between the base core **7** and the core module **11d**, and thus can further reduce loss in the coil unit **6**.

According to the sixth embodiment, the coil apparatus **12e** or **12f**, in which the core segments **1**, **2**, and **3** are bonded to each other, forming gaps between them, eliminates the need for the case **5** for fixing the core segments **1**, **2**, and **3**, and can reduce manufacturing cost. The coil apparatus **12e** or **12f** can eliminate leakage flux from between the base core **7** and the core module **11c** or **11d**, and thus can further reduce loss in the coil unit **6**.

Seventh Embodiment

FIG. 41 is a cross-sectional view of a coil apparatus according to a seventh embodiment of the present invention. In a coil apparatus **12g** according to the seventh embodiment, the plurality of core segments **1**, **2**, and **3** is fixed to a metal plate **160d**. In the seventh embodiment, the same reference numerals are assigned to the same components as those in the first to sixth embodiments, and a configuration different from that of the first to sixth embodiments will be mainly described. The metal blocks **160b** that support the metal plate **160d** are erected on the metal housing **160**.

FIG. 42 is an enlarged view illustrating the metal plate as viewed from below, on which the coil apparatus illustrated in FIG. 41 is provided. FIG. 43 is an enlarged view illustrating the metal plate as viewed from the side, on which the coil apparatus illustrated in FIG. 41 is provided. The metal plate **160d** includes ribs **165** for positioning the plurality of core segments **1**, **2**, and **3** in the X-axis direction.

The ribs **165** are formed on a surface of the metal plate **160d** facing the core module **11e**. The ribs **165** have a thickness of 1 mm or less in the X-axis direction. The core segments **1**, **2**, and **3** are stuck between the ribs **165** using an adhesive **4d**. The core segments **1**, **2**, and **3** are positioned by the ribs **165** in the X-axis direction, so that gaps are formed between the core segments **1**, **2**, and **3**.

By the sticking of the core segments **1**, **2**, and **3** to the metal plate **160d**, the core segments **1**, **2**, and **3** are fixed in the core module **11e**. Since the core segments **1**, **2**, and **3** are fixed by the metal plate **160d**, it is not necessary to provide the case **5** in the coil apparatus **12g** for fixing the core segments **1**, **2**, and **3**. In this case, the manufacturing cost of the case **5** and a mold for processing the case **5** are unnecessary, and thus the core module **11e** can reduce manufacturing cost. Further, the coil apparatus **12g** can eliminate gaps between the base core **7** and the core module **11e**. The coil apparatus **12g** can eliminate leakage flux from between the base core **7** and the core module **11e**, and thus can further reduce loss in the coil unit **6**.

In general, if metal objects are disposed to block the magnetic paths **9**, the electrical characteristics of the coil apparatus **12g** will be affected. In the seventh embodiment, the ribs **165** are located in outer edge portions of the annular magnetic paths **9**. In the annular magnetic paths **9**, magnetic flux passes through the inner side of the center of the magnetic paths **9** in cross section. Thus, the coil apparatus **12g** can eliminate the influence of the provision of the ribs **165** that are metal objects in the magnetic paths **9**, on the electrical characteristics.

The direction of the magnetic paths **9** in the core module **11e** is the X-axis direction, whereas the thickness direction of the adhesive **4d** is the Y-axis direction. When the thickness of the adhesive **4d** varies, the core segments **1**, **2**, and **3** vary in position in the Y-axis direction, but do not vary in

position in the X-axis direction. Thus, even if the thickness of the adhesive 4d varies, it does not affect the length of the core gaps. Therefore, the coil apparatus 12g can eliminate the influence of variations in the thickness of the adhesive 4d on the inductance value.

FIG. 44 is a cross-sectional view illustrating a coil apparatus according to a first modification of the seventh embodiment during assemblage. FIG. 45 is a cross-sectional view illustrating an assembled state of the coil apparatus illustrated in FIG. 44. In a coil apparatus 12h, the core segments 1 and 2 are not disposed above the legs of the base core 7. The core segments 3 are stuck to a metal plate 160e. The metal plate 160e to which the core segments 3 are stuck is fixed to the metal blocks 160b by tightening the screws 10a. By fixing the metal plate 160e to the metal blocks 160b, the legs of the base core 7 come into contact with the ribs 165. The ribs 165 form gaps between the legs of the base core 7 and the core segments 3.

Also in the first modification of the seventh embodiment, the coil apparatus 12h can eliminate the influence of the provision of the ribs 165 in the magnetic paths 9 on the electrical characteristics. The coil apparatus 12h can eliminate the influence of variations in the thickness of the adhesive 4d on the inductance value. Further, since there are no core segments 1 and 2 above the legs of the base core 7, the coil apparatus 12h can eliminate variations in the length of gaps above the legs. Consequently, the coil apparatus 12h can further reduce variations in inductance value.

FIG. 46 is a cross-sectional view of a coil apparatus according to a second modification of the seventh embodiment. A metal plate 160f is the metal plate 160d with radiating fins 166 added to the top face. By fixing the core segments 3 to the metal plate 160f having the radiating fins 166, heat dissipation from the core segments 3 can be accelerated.

According to the seventh embodiment, by fixing the core segments 1, 2, and 3 to the metal plate 160d, 160e, or 160f provided with the ribs 165, the coil apparatus 12g, 12h, or 12i eliminates the need for the case 5 for fixing the core segments 1, 2, and 3, and can reduce manufacturing cost. The coil apparatus 12g, 12h, or 12i can eliminate leakage flux from between the base core 7 and the core module 11e or 11f, and thus can further reduce loss in the coil unit 6. The coil apparatus 12g, 12h, or 12i can fix the core segments 1, 2, and 3 with the core gaps of a desired length provided between them, and can reduce variations in inductance value.

Eighth Embodiment

FIG. 47 is an exploded view of a coil apparatus according to an eighth embodiment. FIG. 48 is a cross-sectional view illustrating an assembled state of the coil apparatus illustrated in FIG. 47. A coil apparatus 20 according to the eighth embodiment is not provided with the base core 7. In the coil apparatus 20, the magnetic paths 9 are formed only by a plurality of core segments 1c, 2c, and 3c. In the eighth embodiment, the same reference numerals are assigned to the same components as those in the first to seventh embodiments, and a configuration different from that of the first to seventh embodiments will be mainly described.

The coil apparatus 20 includes a core module 21 and the coil unit 6. The core module 21 includes a core segment group that is the plurality of core segments 1c, 2c, and 3c, and a case 22 that holds the core segment group. The core segment group includes two core segments 1c, one core segment 2c, and any number of core segments 3c. Each of

the two core segments 1c constitutes an outer leg 26. The core segment 2c constitutes a center leg 25. The core module 21 forms the two magnetic paths 9 that are both closed magnetic paths.

5 In the core segment group, a plurality of core segments 3c provided in place of the base core 7 illustrated in FIG. 4 constitute a first core component. The core segments 3c are aligned in the X-axis direction with gaps between them. Of the core segments 3c included in the core segment group, 10 core segments 3c other than the core segments 3c constituting the first core component constitute a second core component. The core segments 3c and the core segments 1c and 2c constituting the second core component are aligned in the X-axis direction with gaps between them. The core segments 3c constituting the first core component are disposed in the lower part of the case 22. The core segments 3c constituting the second core component are disposed in the upper part of the case 22.

The height of each core segment 1c in the Y-axis direction 20 is larger than the height of each core segment 3c in the Y-axis direction. The height of the core segment 2c in the Y-axis direction is larger than the height of each core segment 3c in the Y-axis direction. The height of each core segment 1c in the Y-axis direction and the height of the core segment 2c in the Y-axis direction are the same. Here, dimensional differences of about $\pm 3\%$ between the core segments 1c and the core segment 2c due to dimensional tolerances at the time of manufacturing are ignored. The height of each core segment 1c and the height of the core segment 2c being the same 25 includes the case where there are dimensional differences of about $\pm 3\%$.

Each of the core segments 1c, 2c, and 3c is smaller than the base cores 7, 7a, 7b, 7c, and 7d of the first to seventh embodiments, and thus is easy to fire as compared with the 30 base cores 7, 7a, 7b, 7c, and 7d. The core segments 1c, 2c, and 3c can reduce loss in the coil unit 6 as compared with the base cores 7, 7a, 7b, 7c, and 7d. By using the core segments 1c, 2c, and 3c, the core module 21 can increase dimensional accuracy and can shorten firing time.

40 The coil apparatus 20 can reduce the dimensional tolerances of the core segments 1c, 2c, and 3c, and thus can reduce variations in inductance value. The coil apparatus 20 can eliminate the need for core polishing, which has conventionally been performed to reduce dimensional tolerances, and thus allows a reduction in the processing time of the core module 21 and a reduction in manufacturing cost.

45 Either the general-purpose ferrite core material or the low-loss ferrite core material may be used for the core segments 1c, 2c, and 3c. Since both the general-purpose ferrite core material and the low-loss ferrite core material 50 can be used, the number of procurement sources from which the material of the core segments 1c, 2c, and 3c can be procured increases. Consequently, the procurement of components for manufacturing the core module 21 can be 55 stabilized, and the procurement cost can be reduced. Further, the core module 21 can be reduced in loss in the coil unit 6 and improved in quality.

When the case 22 is viewed from a position away from the case 22 in the Z-axis direction, the outer edge of the case 22 60 has a rectangular shape. The case 22 has a three-dimensional shape surrounding a hollow portion 24. Spaces in which the core segments 1c, 2c, and 3c are disposed are provided around the hollow portion 24. The case 22 includes divider plates 23. The divider plates 23 separate adjacent core segments of the core segments 1c, 2c, and 3c from each other in the X-axis direction. The case 22 is a component 65 molded in one piece including the divider plates 23. Since

the case 22 is molded in one piece including the divider plates 23, the core module 21 can reduce manufacturing cost. The divider plates 23 may be components formed separately from the case 22.

The case 22 may include the ribs 13 illustrated in FIGS. 12 and 13 instead of the divider plates 23. By the provision of the ribs 13, each of the plurality of core segments 1c, 2c, and 3c is positioned in the X-axis direction. The case 22 is molded in one piece including the ribs 13, so that the core module 21 can reduce manufacturing cost.

Further, the lid 8 illustrated in FIG. 14 may be attached to the case 22. The lid 8 covers the spaces in which the core segments 1c, 2c, and 3c disposed in the upper part of the case 22 are accommodated. By the provision of the lid 8, if any of the core segments 1c, 2c, and 3c is damaged, the coil apparatus 20 can prevent a broken piece produced by the damage from flying to the outside of the case 22.

The core segments 1c are passed through portions of the case 22 corresponding to the short sides of the rectangle. The core segment 2c passes through the case 22 and the hollow portion 24 in the center of the case 22 in the X-axis direction. The coil unit 6 is disposed through the hollow portion 24. The coil unit 6 is installed in the coil apparatus 20 in a state the core segment 2c has passed through the opening of the coil unit 6. When the core module 21 is being assembled, the core segment 2c is fitted into the case 22 after the coil unit 6 is disposed in the hollow portion 24. The core segments 1c and the core segments 3c are fitted into the case 22 in any order.

In the core module 21, the magnetic paths 9 are formed by the core segments 1c, 2c, and 3c, so that core gaps between the core segments are provided in the entire magnetic paths 9. Thus, the number of core gaps in the entire magnetic paths 9 is larger than that in the case where core gaps between core segments are provided only in part of the magnetic paths 9. The coil apparatus 20 can reduce length per core gap because it can increase the number of core gaps. By shortening the core gaps, the coil apparatus 20 can reduce magnetic flux leaking from the core gaps, and can reduce eddy-current loss in the coil unit 6.

The core segments 1c, 2c, and 3c constituting the first core component are held with the lower surfaces of the core segments 1c, 2c, and 3c exposed to the outside of the case 22 at the bottom of the case 22. The coil apparatus 20 is installed in the metal housing 160 with the lower surfaces of the core segments 1c, 2c, and 3c in contact with the metal housing 160. Thus, in the coil apparatus 20, some core segments included in the core segment group are disposed to be able to be thermally coupled to the metal housing 160 that is an external structure of the case 22. Heat-conductive grease or a heat dissipation sheet may be sandwiched between the lower surfaces of the core segments 1c, 2c, and 3c and the metal housing 160.

The metal housing 160 has a configuration for fixing the coil apparatus 20 and also serves as a cooler. The coil apparatus 20 is assembled with some core segments included in the core segment group thermally coupled to the metal housing 160. Consequently, the coil apparatus 20 can obtain high heat dissipation by the use of the metal housing 160.

The coil apparatus 20 is fixed to the metal housing 160 when the coil apparatus 20 is assembled. The coil apparatus 20 may be fixed to the metal housing 160 after the assembly of the coil apparatus 20 is completed. Thus, the degree of freedom in the assembly order of the coil apparatus 20 is improved, so that a more efficient assembly order can be

selected to manufacture the coil apparatus 20. This allows a reduction in the manufacturing time of the coil apparatus 20.

The core segment group constituting the core module 21 may include the sheet-shaped core segments 3b illustrated in FIG. 9. By including the plurality of core segments 3b in the core segment group, the core module 21 can distribute core gaps in the magnetic paths 9 among more gaps. Consequently, the core module 21 can reduce leakage flux to reduce loss in the coil unit 6.

10 FIG. 49 is an exploded view of a coil apparatus according to a first modification of the eighth embodiment. In FIG. 49, the coil unit 6 is omitted. In a coil apparatus 20a according to the first modification of the eighth embodiment, cutouts 27 are formed in a case 22a constituting a core module 21a. 15 The cutouts 27 are formed in both side faces of the case 22a in the X-axis direction. By cutting the side faces of the case 22a in the Y-axis direction, parts of the side faces are cut to form the cutouts 27.

By the formation of the cutouts 27 in the case 22a, the coil 20 apparatus 20a can improve heat dissipation. By the provision of the cutouts 27, the amount of material used for manufacturing the case 22a can be reduced. The position, shape, and number of the cutouts 27 can be set as desired so as to prevent the core segments 1c, 2c, and 3c in the case 22a 25 from passing through the cutouts 27 and falling off. Further, by the provision of the cutouts 27, it can be visually checked from the outside of the case 22a how the core segments 1c, 2c, and 3c are fitted into the case 22a. Consequently, poor assembly of the core segments 1c, 2c, and 3c can be 30 prevented from being left unnoticed.

FIG. 50 is an exploded view of a coil apparatus according to a second modification of the eighth embodiment. FIG. 51 is a cross-sectional view illustrating an assembled state of the coil apparatus illustrated in FIG. 50. In FIG. 50, the coil 35 unit 6 is omitted. The magnetic paths 9 in a coil apparatus 20b according to the second modification of the eighth embodiment include points at which adjacent core segments are in contact with each other.

In the coil apparatus 20b, a case 22b constituting a core 40 module 21b is not provided with the divider plates 23 for separating the core segments 1c from the core segments 3c. Further, the case 22b is not provided with the divider plates 23 for separating the core segment 2c from the core segments 3c. Each core segment 1c constituting the core module 21b is in contact with each of the two core segments 3c adjacent to the core segment 1c. The core segment 2c constituting the core module 21b is in contact with each of the four core segments 3c adjacent to the core segment 2c.

50 Edges of the coil unit 6 are susceptible to magnetic flux, and thus loss in the coil unit 6 tends to occur at the edges. As illustrated in FIG. 51, in the magnetic paths 9, points at which the core segments 1c are in contact with the core segments 3c are positions close to outer peripheral edges 6a of the coil unit 6. Since core gaps are not provided at the 55 positions close to the edges 6a, magnetic flux passing through the edges 6a can be suppressed. In the magnetic paths 9, points at which the core segment 2c is in contact with the core segments 3c are positions close to inner peripheral edges 6b of the coil unit 6. Since core gaps are not provided at the positions close to the edges 6b, magnetic flux passing through the edges 6b can be suppressed. Thus, the coil apparatus 20b can suppress the occurrence of eddy currents in the edges 6a and 6b, and can reduce loss in the coil unit 6.

60 In the example illustrated in FIGS. 50 and 51, adjacent core segments are in contact with each other at four points in each magnetic path 9. In each magnetic path 9, adjacent

core segments may be in contact with each other at any point. Further, the number of points at which adjacent core segments are in contact with each other is not limited to four, and may be any. Suffice for each magnetic path 9 to include at least one point at which adjacent core segments are in contact with each other. Consequently, the coil apparatus 20b can suppress the occurrence of eddy currents in the coil unit 6, and can reduce loss in the coil unit 6.

FIG. 52 is an exploded view of a coil apparatus according to a third modification of the eighth embodiment. FIG. 53 is a cross-sectional view illustrating an assembled state of the coil apparatus illustrated in FIG. 52. In FIG. 52, the coil unit 6 is omitted. In a coil apparatus 20c according to the third modification of the eighth embodiment, a core module 21c does not use the core segment 2c illustrated in FIG. 47. The core module 21c is composed of four core segments 1c and any number of core segments 3c. The center leg 25 consists of two core segments 1c aligned in the X-axis direction.

Since the core module 21c does not use the core segment 2c, the number of types of components is reduced as compared with those of the core modules 21, 21a, and 21b described above. By the reduction of the number of types of components constituting the core module 21c, the productivity of the core module 21c can be improved, and the manufacturing cost of the core module 21c can be reduced.

FIG. 54 is an exploded view of a coil apparatus according to a fourth modification of the eighth embodiment. FIG. 55 is a cross-sectional view illustrating an assembled state of the coil apparatus illustrated in FIG. 54. In FIG. 54, the coil unit 6 is omitted. In a coil apparatus 20d according to the fourth modification of the eighth embodiment, a core module 21d is provided with a plurality of core segments 3d in place of the core segments 1c, 2c, and 3c illustrated in FIG. 47. The core module 21d is composed of the core segments 3d of one type.

The XY plane of each core segment 3d is rectangular. The long side of the rectangle is longer than the short side of the rectangle, and has a length up to about twice that of the short side. Of the plurality of core segments 3d constituting the core module 21d, core segments 3d constituting the center leg 25 and core segments 3d constituting the outer legs 26 are disposed with their long sides aligned with the Y-axis direction. Of the plurality of core segments 3d constituting the core module 21d, core segments 3d other than the core segments 3d constituting the center leg 25 and the core segments 3d constituting the outer legs 26 are disposed with their long sides aligned with the X-axis direction.

A case 22d is configured so that the core segments 3d whose long-side directions are determined as described above can be disposed therein. By the disposition of the core segments 3d whose long sides are aligned with the Y-axis direction at the center leg 25 and the outer legs 26, spaces in which the coil unit 6 is disposed are provided between the core segments 3d disposed in the upper part of the case 22d and the core segments 3d disposed in the lower part of the case 22d.

The core module 21d is reduced in the number of types of components as compared with the core modules 21, 21a, 21b, and 21c described above. By the reduction of the number of types of components constituting the core module 21d, the productivity of the core module 21d can be improved, and the manufacturing cost of the core module 21d can be reduced.

FIG. 56 is an exploded view of a coil apparatus according to a fifth modification of the eighth embodiment. FIG. 57 is a cross-sectional view illustrating an assembled state of the coil apparatus illustrated in FIG. 56. In FIG. 56, the coil unit

6 is omitted. In a coil apparatus 20e according to the fifth modification of the eighth embodiment, a core module 21e is composed of the core segments 3d of one type. Of the core segments 3d constituting the core module 21e, core segments 3d disposed in the upper part of a case 22e are all disposed with their long sides aligned with the Y-axis direction.

Core segments 3d disposed in the lower part of the case 22e are disposed in the same manner as the core segments 3d disposed in the lower part of the case 22d in the fourth modification. That is, of the core segments 3d disposed in the lower part of the case 22e, core segments 3d constituting the center leg 25 and core segments 3d constituting the outer legs 26 are disposed with their long sides aligned with the Y-axis direction. Of the core segments 3d disposed in the lower part of the case 22e, core segments 3d other than the core segments 3d constituting the center leg 25 and the core segments 3d constituting the outer legs 26 are disposed with their long sides aligned with the X-axis direction.

The case 22e is configured so that the core segments 3d whose long-side directions are determined as described above can be disposed therein. Of the core segments 3d disposed in the lower part of the case 22e, the core segments 3d constituting the center leg 25 and the core segments 3d constituting the outer legs 26 are disposed with their long sides aligned with the Y-axis direction, so that spaces in which the coil unit 6 is disposed are provided between the core segments 3d disposed in the upper part of the case 22e and the core segments 3d disposed in the lower part of the case 22e. Like the core module 21d in the fourth modification of the eighth embodiment, the core module 21e can reduce the number of types of components constituting the core module 21e. Consequently, the productivity of the core module 21e can be improved, and the manufacturing cost of the core module 21e can be reduced.

By the disposition of the core segments 3d whose long sides are all aligned with the Y-axis direction in the upper part of the case 22e, the cross-sectional area of the magnetic paths 9 in the upper part of the core module 21e is about one to two times larger than that when the core segments 3d whose long sides are aligned with the X-axis direction are disposed. By the reduction of magnetic flux density in the upper part of the core module 21e, the coil apparatus 20e can reduce loss in the coil unit 6 in the core module 21e. The coil apparatus 20e can reduce the amount of heat generation and the density of heat generation in the core module 21e, and can reduce a temperature rise in the core module 21e. Consequently, the coil apparatus 20e eliminates the need to cool the core module 21e by placing the core module 21e in contact with a structure such as the metal plate 160a illustrated in FIGS. 18 and 19, the metal structure 160c illustrated in FIG. 20, or the metal structure 160g illustrated in FIG. 21.

Further, by the elimination of the need to cool the core module 21e by placing the core module 21e in contact with the structure, the coil apparatus 20e can be fixed using the metal spring 14 illustrated in FIG. 22 or the like. By using the metal spring 14, the power converter 100 allows a reduction in manufacturing cost and reductions in the size and weight of the power converter 100.

As in the second modification of the eighth embodiment, the magnetic paths 9 in the coil apparatuses 20a, 20c, 20d, and 20e according to the first modification of the eighth embodiment and the third to fifth modifications of the eighth embodiment may include at least one point at which adjacent core segments are in contact with each other. This allows the coil apparatuses 20a, 20c, 20d, and 20e to

suppress the occurrence of eddy currents in the coil unit 6 to reduce loss in the coil unit 6.

As in the second modification of the eighth embodiment, the magnetic paths 9 in the coil apparatuses 12, 12a, 12b, 12c, 12d, 12g, 12h, and 12i according to the first to fifth embodiments and the seventh embodiment may include at least one point at which adjacent core segments are in contact with each other. This allows the coil apparatuses 12, 12a, 12b, 12c, 12d, 12e, 12f, 12g, 12h, and 12i to suppress the occurrence of eddy currents in the coil unit 6 to reduce loss in the coil unit 6. 10

The configurations described in the above embodiments illustrate an example of the subject matter of the present invention, and can be combined with another known art, and can be partly omitted or changed without departing from the 15 scope of the present invention.

The invention claimed is:

1. A power converter comprising:
 a switching element;
 a cooler; and
 a coil apparatus installed on a surface of the cooler,
 the coil apparatus including:
   a coil;
   a first core component including a leg around which the
   coil is wound;

a second core component that includes a plurality of first core segments arranged in a row with gaps between the first core segments, and is connected to the leg of the first core component to form a magnetic path together with the first core component; and a first case that holds the plurality of first core segments and includes divider plates to separate adjacent first core segments of the plurality of first core segments from each other, a first pair of side walls provided at both ends of the first core component in a direction along the magnetic path, and a second pair of side walls provided at both ends of the first core component in a direction perpendicular to the magnetic path, the first pair of side walls and the second pair of side walls having a height greater than or equal to a height of the divider plates, wherein

the cooler is thermally connected to the first core component, and

the first case is formed of a non-magnetic material.

2. The power converter according to claim 1, wherein, of the plurality of first core segments, a first core segment connected to the leg has an area of a surface of the first core segment connected to the leg larger than or equal to an area of a surface of the leg connected to the first core segment.

3. The power converter according to claim 1, wherein the plurality of first core segments comprises core segments of one type.

4. The power converter according to claim 1, wherein a thickness of the plurality of first core segments in a height direction is larger than a thickness of a thin-walled portion of the first core component.

5. The power converter according to claim 1, wherein a lid is attached to the first case to cover a space in which the plurality of first core segments is accommodated.

6. The power converter according to claim 1, wherein material of the first case includes a liquid crystal polymer, polyphenylene sulfide, or polybutylene terephthalate.

7. The power converter according to claim 1, further comprising:

a metal housing that is the cooler; and
 a metal structure fixed to the metal housing to cover the
 coil apparatus.

8. The power converter according to claim 1, wherein, in an extending direction of the leg around which the coil is wound, the coil is wound around on the cooler side of a center of the leg.
